UNITED STATES PATENT OFFICE.

CHARLES C. JACOBS, OF CHICAGO, ILLINOIS, ASSIGNOR TO F. C. AUSTIN DRAINAGE EXCAVATOR COMPANY, OF CHICAGO, ILLINOIS, A CORPORATION OF ILLINOIS.

EXCAVATOR.

No. 885,757.

Specification of Letters Patent.

Patented April 28, 1908.

Application filed June 15, 1907. Serial No. 379,203.

To all whom it may concern:

Be it known that I, CHARLES C. JACOBS, a citizen of the United States, residing at Chicago, in the county of Cook and State of Illinois, have invented certain new and useful Improvements in Excavators, of which the following is a specification.

My invention relates to excavators or ditch digging machines, and concerns more particularly the bucket or shovel and the means for discharging or dumping its load.

I have found it advisable to have both ends of the bucket open, one end having one or more sharp cutting edges and adapted to receive the dirt, while the other or rear end is normally closed by a hood. The bucket is pivoted or hinged or otherwise mounted so as to be movable whereby its rear open end may be moved or tilted away from the hood, which action permits the discharge of the load. Preferably the forward mouth or entrance to the bucket has a plurality of cutting edges so that when one becomes unduly dulled or unfit for further service without sharpening I may change or reverse the position of the bucket to bring another sharp edge into action.

On the accompanying drawings, forming a part of this specification, I have illustrated two preferred and desirable embodiments of my invention, like reference characters referring to the same parts throughout.

On these drawings Figure 1 is a side elevation of one form of my improved type of bucket and illustrates also the means for tilting the same to discharge or dump its load; Fig. 2 is a view similar to Fig. 1 and shows the bucket or shovel in discharging position; Fig. 3 is a plan view of the bucket, its truck, a portion of the track-way of the bucket, and a means for tilting the bucket; Fig. 4 is an elevation on a reduced scale of an excavator in which my improved forms of bucket are suitable for use; Fig. 5 is a side elevation of a modified form of bucket and tilting mechanism; and Fig. 6 is a cross-section illustrating the co-operation of the truck wheel on one side of the truck with the track-way and the track and co-acting mechanism for tilting the bucket.

The buckets described below and illustrated on the drawings are each mounted on a truck adapted to travel or reciprocate on a track-way 10 (Fig. 4) of an excavator shaped to correspond or conform substantially to

the outline or cross-sectional profile of the ditch or trench to be dug. This form of excavator is now well known in the art, but it should be understood that the track-way 10 is fed downwardly step by step by suitable mechanism to permit the bucket to scrape off successive layers of dirt and convey the excavated material over the banks upon which it is dumped. The track-way 10 consists of a track plate 11 on each side of the bucket, each having riveted thereto top and bottom angle bars 12 and 13 which in conjunction with the plate 11 form one side of the track-way. The bucket truck adapted to travel or reciprocate on this track-way consists of a pair of side channel bars 13^a suitably connected together at their forward and rear ends by the cross channel bars 14, 15, 16, and 17. As is illustrated in Figs. 1, 2, and 3 the forwardly pulling or advancing cable 18 is attached by suitable means to the channel bar 14, while the retracting cable 19 is similarly secured to the cross channel bar 17. The truck is provided with front and rear axles 20 and 21 respectively, the outer ends of each of which are equipped with flanged wheels 22 which travel between the angle bars 12 and 13 resting upon the latter and being kept down to compel the shovel to perform its work by the former.

Fastened to the inner faces of the webs of the truck side channel bars 13^a by the rivets 23 is a hood 24 having a rear vertically-curved wall 25, and having depending from the channel bars 13^a a pair of supporting portions or ears 26 to which the bucket 27 is pivoted or hinged at 28. The hood 25 overlaps and closes the rear open mouth or exit 28^a of the bucket when the latter is in the position shown in Fig. 1, which is its normal load-retaining position. As is indicated in Fig. 2 the side walls 29 of the bucket have their rear ends curved concentric to the pivot or hinge 28, which is the same curvature as the rear wall 25 of the hood so that the latter is permitted to completely close the discharge mouth 28. The bucket 27, as stated above, has the side walls 29 and also has a top wall 30 and a bottom 31, the forward end 32 of the bucket being open and equipped at its top and bottom edges 33 and 34 with sharp cutting edges, either or both of which may be serrated or notched as the edge 33 is shown in Fig. 3. The pivot 28 is midway between the top and bottom walls 30 and 31.

of the bucket, which permits the latter to be reversed in position if desired, whereby when the cutting edge 34 has become dulled or unsuitable for further use the other edge 33 5 may be brought into action. This dismounting and reversal of the bucket can be readily and easily accomplished, in fact can be more quickly done than would be required to sharpen the dull edge. In some cases it is 10 impossible to resharpen the edge, owing to the extent to which it has been worn away by its action in the dirt.

At the position on the excavator where it is desired to dump the bucket, I have affixed 15 to the outer faces of the track plates 11 upright standards 35 in which is mounted a transverse shaft 36 on which is loosely mounted a depending hook 37 which is held from movement lengthwise shaft 36 by the 20 collars 38 at its opposite sides. On the top of the bucket and extended transversely thereto sufficiently to overlap the top flanges of the truck side channels 13^a I provide a bar 39 which limits the downward turning of the 25 bucket on its hinges or pivots 28, the bucket at the same time however being permitted to tilt upwardly to ride over obstructions. Also on the top of the bucket I mount a catch 40 which coöperates with the hook 37. 30 A standard 41 consisting of a bent plate slotted at 42 so as to escape the hook 37 is mounted on the rear central portion of the truck, the standard being adapted to coöperate with a transversely-extended plate 43 35 fastened to the hook 37.

The operation of this mechanism is substantially as follows: The truck and its attached bucket are reciprocated on the track-way 10 by the advancing and retracting 40 cables 18 and 19 operated by suitable mechanism not shown in detail. During the forward travel of the bucket in the trench its lower sharp edge shaves off a layer of earth, the dirt being received in the bucket and retained 45 therein because of the closure of the rear mouth 28^a by the curved hood 25. When the truck and attached bucket reach the position on the track-way where the load should be dumped, the hook 37 engages the 50 catch 40 and lifts the forward end of the bucket, tilting it upon its pivots or hinges 28. This rocking of the bucket moves its rear end 28^a away from the hood 25 so that the dirt or load may drop therethrough. In this 55 dumping operation the bucket is not quite brought to vertical position, so that if it is released it will automatically rock or tilt to the normal load-retaining position indicated in Fig. 1. To release the hook 37 from the 60 catch 40 the standard 41 is provided, the upper end of which strikes the plate 43 and lifts the hook sufficiently to free the catch 40 and the bucket therefrom, the latter dropping to normal position as soon as free.

65 In Figs. 5 and 6 I have illustrated a modi-

fication in the means for tilting the bucket, other parts of the mechanism being substantially as described above. In this modification instead of using a pivoted hook to tilt the bucket I employ a track 44, on each side 70 of the track-way 10, which has upper and lower angle bars 45 and 46. Journaled on the top of the bucket in bearings 47 is a transverse shaft 48 having at its opposite ends rollers 49 which coöperate with the tracks 75 44, that is travel between the angle bars 45 and 46. It will be noted, as shown in Fig. 5, that the track 44 is bowed upwardly at the position where it is desired to tilt the bucket, and as the truck and its attached bucket 80 travel up or along the track-way 10 the rollers 49 are lifted when they engage the arch angle bar 49, and by their movement and co-operation with the track 44 tilt the bucket to the discharge position shown in Fig. 5. 85 When the truck and bucket travel rearwardly the bucket is brought to normal position by the unbowed portions of the tracks 44. This latter form of device is somewhat simpler than the other and in some respects is more 90 preferable.

I desire to have it understood that this invention is not limited and restricted to the precise details of construction shown and described, but that these details may be 95 varied within wide limits without departure from my invention.

I claim:

1. The combination of an excavating bucket having an open rear end, a hood or 100 closure for said open end, and means to move said bucket so that the hood or closure no longer closes its rear open end whereby the contents may be discharged, substantially as described.

2. The combination of a pivoted or hinged excavating bucket having an open rear end, a hood or closure for said open end, and means to tilt said bucket on its pivots or 105 hinges so that the hood or closure no longer closes its rear open end whereby the contents may be discharged, substantially as described.

3. The combination of a pivoted or hinged bucket having an open front mouth with a 110 sharp cutting edge and an open rear end, a hood or closure for said open end, and means to tilt said bucket on its pivots or hinges so that the hood or closure no longer closes its rear open end whereby the contents may be 115 discharged, substantially as described.

4. The combination of a truck, an excavating bucket pivoted or hinged to said truck and having an open front mouth with a sharp cutting edge and an open rear end, a hood or closure for said open end, and means to tilt 120 said bucket on its pivots or hinges so that the hood or closure no longer closes its rear open end whereby the contents may be discharged, substantially as described.

130

5. The combination of a trackway shaped to conform substantially to the cross-sectional outline of the trench to be dug; a truck adapted to travel on said trackway, an excavating bucket pivoted or hinged to said truck and having an open front mouth with a sharp cutting edge and an open rear end, a hood or closure for said open end, and means to tilt said bucket on its pivots or hinges so that the hood or closure no longer closes its rear open end whereby the contents may be discharged, substantially as described.

10 6. The combination of a trackway, a hinged bucket adapted to travel on said trackway, said bucket having an open rear end, a hood or closure for said open end, a track, and means coöperating with said track to tilt said bucket so that the hood or closure no longer closes its rear open end whereby the contents 15 may be discharged, substantially as described.

20 7. The combination of a trackway shaped to conform substantially to the cross-sectional profile or outline of the trench to be

dug, a truck adapted to travel on said trackway, an excavating bucket hinged to said truck, said bucket having an open front end with a sharp cutting edge and an open rear end, a hood mounted on said truck and adapted normally to close the rear open end of said bucket, a track, and means coöperating with said track to tilt said bucket so that the hood no longer closes its rear open end whereby the contents may be discharged, substantially as described.

25 8. In an excavator, the combination of a support, and a bucket mounted on said support and having an open mouth with a plurality of cutting edges whereby when the active edge becomes dull the position of the bucket 30 may be changed or reversed to render one of the other cutting edges operative, when the bucket travels in the same direction as before, substantially as described.
